UNITED STATES PATENT OFFICE.

WILLIAM C. J. GUILFORD, OF HARRISON, MAINE.

HAND-OPERATING MASSAGING APPARATUS.

1,253,230.

Specification of Letters Patent. Patented Jan. 15, 1918.

Application filed May 18, 1916. Serial No. 98,350.

To all whom it may concern:

Be it known that I, WILLIAM C. J. GUILFORD, citizen of the United States, residing at Harrison, in the county of Cumberland and State of Maine, have invented certain new and useful Improvements in Hand-Operating Massaging Apparatus, of which the following is a specification, reference being had therein to the accompanying drawing.

This invention relates to improvements in massaging apparatus and has for its primary object the provision of what I may appropriately style an actuator for massaging elements, the latter being of an expansible nature such as illustrated in my application executed of even date herewith, and wherein the massaging elements are adapted to engage the abdominal or other portions of the body, and be alternately actuated to subject the parts being treated to a to and fro passive manipulation or exercise.

The actuator of the present invention is designed to operate the expansible massage elements to which I have alluded primarily, though not essentially through the medium of a manual control capable of varying the rapidity of the successive expansions or contractions of the massage element, as distinguished from a uniformity of action under a motor control, as is disclosed in another of my applications, also executed of even date herewith, Serial No. 98352.

The preferred embodiment of the invention comprises a suitable base having a supporting frame or housing thereon for suitably actuating gearing and connections to an operating crank or the like, said housing or equivalent supporting brackets being provided with oppositely disposed rests for a pair of cylinders from which lead the normally closed connections to the expansible massage elements in combination with means for supplying air to the cylinders and connections leading therefrom, all as will be more readily understood from the detailed description hereinafter contained when read in connection with the accompanying drawings forming a part hereof, and wherein the before mentioned embodiment of the invention is illustrated:

In the drawings:

Figure 1 is an elevation of the actuator

and massaging elements, parts being broken away.

Fig. 2 is an end view, parts being broken away; and

Fig. 3 is in part a longitudinal section and side elevation.

Referring more specifically to the drawings wherein like reference characters designate corresponding parts throughout the several views, A represents a suitable base, conveniently of metal to give the same stability. Projecting upwardly from said base, and secured rigidly thereto are front and rear brackets B and C connected at their tops as at D and closed at their sides as at E to constitute a housing and bearing for the operating gearing. Projecting laterally to opposite sides and from the upper portion of the housing or brackets is a pair of cups or rests F in which parallel upright cylinders G are secured, the rests constituting the lower ends of the cylinders and being suitably apertured as at f for the passage of piston rods H pivoted to pistons J adapted to reciprocate in the cylinders and connected to be alternately advanced and retracted relative to each other through the medium of oppositely disposed cranks K connected to the cross shaft L mounted in the housing, this cross shaft having an appropriately centrally disposed pinion M thereon, meshing with a gear N on a shaft O also mounted in the housing in parallel relation to the shaft L and carrying at its outer end a handle P designed for manual rotation to transmit power through the gear, pinion and crank connections to the pistons in the cylinders G.

The upper ends of the cylinders G terminate in nipples Q to which flexible pipes R are secured and respectively lead to the massage elements S having the expansible sheets or diaphragms T sealed upon base members t with a closed space therebetween communicating with the pipe connections R, the details of the massage implements as heretofore observed, being disclosed in my companion application Serial No. 98,353.

U is a storage tank for compressed air, supported upon the base A, preferably in an upright position parallel to the cylinders G, this tank having therein a pump V, the handle v of which projects exteriorly of the tank to be actuated in a manner readily

understood by persons skilled in the art. From the top of the tank U, at the outer edge thereof,—in this instance for the economy of space,—I provide an outlet pipe W 5 feeding to branches w passing around the sides of the tank and delivering to the upper ends of the cylinders G, valves X being adapted to open or close the communication between the tank and the cylinders, and pet cocks X' adapted to open to the atmosphere 10 permitting the air to exhaust from cylinders and pipe connections R to reduce the pressure therein when in operation or to permit all of the air beyond the valve X to escape 15 when the use of the device is completed so as to relieve the massage elements of all internal pressure when not in use.

From the foregoing description the operation of the actuator will be readily understood, it being my desire to manipulate the 20 expandable massage elements through the medium of what may suitably be termed a movable air column or piston, it would be necessary at the outset of a given treatment 25 to introduce that air column into the closed passage intermediate of the expandable sheet or diaphragm and the piston of each cylinder G. This is accomplished by operating the handle P to alternately withdraw the 30 pistons to the lower ends of their respective cylinders when an opening of the proper valve X will permit air from the tank U to enter the cylinder and fill the pipe R leading to and through the massage implement 35 back of the expandable sheet or diaphragm. The valves X are then closed, the massage implement applied to the part to be treated and the handle P rotated to reciprocate the pistons as well as the air column, resulting in the expansion and contraction 40 of each massage implement, and the alternate expansion and contraction of the two massage elements with reference to each other, and at any speed desired, within the 45 capacity of the machine under the manual control as suggested.

The base member A is suitably recessed or grooved as at a to accommodate the cranks in their lowermost position, during rotation.

50 While I have herein disclosed a specific embodiment of the invention it will be understood that said invention is capable of embodiment in other forms and devices as may be included in the hereto appended 55 claims.

What I claim is:

1. The combination with expandable massage elements, and air conducting means leading thereto, of an actuator in communication with said air conducting means comprising a pair of parallel cylinders, supporting means therefor, an air supply leading to said cylinders, pistons in said cylinders, oppositely disposed cranks for operating 60 the pistons, a common shaft for said 65

cranks having a pinion thereon, and a gear for operating said pinion arranged with its axis parallel to the axis of the pinion, substantially as described.

2. The combination with expandable massage elements, and air conducting means leading thereto, of an actuator in communication with said air conducting means comprising a pair of parallel cylinders, supporting means therefor, an air supply leading to said cylinders, pistons in said cylinders, oppositely disposed cranks for operating the pistons, a common shaft for said cranks having a pinion thereon, and a gear for operating said pinion arranged with its axis parallel to the axis of the pinion, in combination with a handle enabling manual operation and control thereof, substantially as described.

3. The combination with expandable massage elements provided with means for connecting them together so that they will be held adjacent to each other in position to conjointly manipulate the same part to be treated and air conducting means leading thereto, of an actuator for said elements comprising a pair of cylinders communicating with said conducting means, pistons in said cylinders, means for actuating said pistons, and means for variably controlling the actuation of said pistons, substantially as described.

4. The combination with expandable massage elements and air conducting means leading thereto, of an actuator for said massage elements including a pair of vertically disposed cylinders in communication with said air conducting means, an air supply leading to said cylinders, reciprocating pistons associated with said cylinders, and means for supporting the cylinders and piston actuating means including a base, a housing thereon and laterally projected rests on said housing to which the lower ends of the cylinders are secured.

5. The combination with expandable massage elements provided with means for connecting them together so that they will be held adjacent to each other in position to conjointly manipulate the same part to be treated and air conducting means leading thereto, an actuator for moving columns of air in said air conducting means and correspondingly expanding and contracting the expandable massage elements, said means being adapted to alternately actuate the massage elements, substantially as described.

6. In combination with expandable massage elements having air conducting means leading thereto, of an actuator for said massage elements comprising a pair of upright cylinders, pistons therein, operating means for the pistons, a source of air supply leading to the cylinders, and means for supporting the cylinders comprising a base, a

- supporting means projecting upwardly therefrom, and laterally projected rests on said supporting means in which the lower ends of the cylinders are secured.
- 5 7. The combination with expandible massage elements, and air conducting means leading thereto, of an actuator for said massage elements comprising a pair of upright cylinders in communication with said
- 10 air conducting means, pistons for said cylinders, operating means for the pistons, and means for supplying air to the cylinders comprising an upright tank for air having a discharge outlet at its rear upper portion,
- 15 branches leading from said discharge around the tank at the oppositely disposed sides thereof and to the cylinders, and suitable valve controlling means, substantially as described.
- 20 8. The combination with expandible massage elements, and air conducting means leading thereto, of an actuator for said massage elements comprising a pair of upright cylinders having their upper ends in communication with said air conducting means, pistons in the cylinders, piston rods extending without the lower ends of the cylinders, a supporting base, a housing projecting upwardly from said base having laterally projected seats in which the lower ends of the cylinders are secured, actuated gearing and connections mounted in the housing for operating the piston rods, means for supplying air to the cylinders including an upright tank for air, and discharge means leading from the tank to the cylinders including suitable valves, controlling means for the passages leading from the tank to the cylinders and for permitting exhaust of the air behind the massage elements when a treatment is completed.
- 25 9. The combination with expandible mas-
- sage elements, and air conducting means leading thereto, of an actuator for said massage elements comprising a pair of upright cylinders having their upper ends in communication with said air conducting means, pistons in the cylinders, piston rods extending without the lower ends of the cylinders, a supporting base, a housing projecting upwardly from said base having laterally projected seats in which the lower ends of the cylinders are secured, actuated gearing and connections mounted in the housing for operating the piston rods, means for supplying air to the cylinders including an upright tank for air, and discharge means leading from the tank to the cylinders including suitable valves, controlling means for the passages leading from the tank to the cylinders and for permitting exhaust of the air behind the massage elements when a treatment is completed.
- 30 10. The combination with alternately expandible coöperating massage elements provided with means for connecting them together so that they will be held adjacent to each other in position to conjointly manipulate the same part to be treated and air conducting means leading thereto, of an actuator for said elements comprising a pair of cylinders communicating with said conducting means, pistons in said cylinders, means for actuating said pistons, and means for variably controlling the actuation of said pistons, substantially as described.
- 35 In testimony whereof I hereunto affix my signature in the presence of two witnesses.
- 40 WILLIAM C. J. GUILFORD.
